BOLT AND ROD NIPPERS

John J. Eyre, East Saugus, Mass.

Application September 15, 1933, Serial No. 689,667

10 Claims. (Cl. 81—199)

The invention relates to so-called bolt and rod cutters for cutting metal stock, and in the present showing, the tool is of the type in which two cutting levers having cutting blades at their front ends, have a power multiplying toggle connection with the front ends of the two hand levers. With such tools, it is ordinarily necessary to open the hand levers into substantially 100° relation with each other to allow the maximum sized stock to be cut by the tool, to be received between the cutting blades. With the hand levers so widely separated, they have very little leverage on the cutting blades, and the most effective leverage does not begin until said hand levers have been closed into approximately 55° or 60° relation with each other. It is thus very difficult to cut relatively large stock with the conventional tools now used. It is one object of the present invention, however, to provide an improved tool in which the hand levers need be opened only into substantially 55° or 60° relation with each other, allowing the stock to be much more easily cut.

Nippers having transversely V-shaped cutting blades do not cut entirely through large stock, but partially cut and partially wedge the stock apart until it finally breaks before the most effective leverage of handle movement has been obtained toward the end of the cutting operation. This break occurs before the cutting edges of the tool come together. Therefore, it is practicable to have these blades in such relation that they will stand partly open when the hand levers are fully closed. The cutting blades however, are disposed in such forwardly diverging relation that they will open sufficiently at their front ends to receive the maximum sized stock, when the hand levers are opened only to about 55° or 60°. With the stock between the front ends of the blades, the hand levers are closed, causing said blades to form two grooves in the stock. The hand levers are then again opened to about the same extent as before and the tool is shifted forwardly onto the stock until the cutting edges of said blades again contact with the stock in the bottoms of the grooves, whereupon the hand levers are again closed, causing the blades to further cut through the stock. These operations are repeated as many times as necessary until the stock is finally cut sufficiently deep to break apart during the last cut, and it will be obvious that the cutting operation may be performed much more easily in this step-by-step manner, opening the hand levers only into approximately 60° relation, than when cutting with one operation

necessitating initial opening of said hand levers into substantially 100° relation. In fact, large stock can be cut with so little strain upon the tool that it is practicable to form the latter of unusually light construction, using aluminum 60 alloy or other relatively light metal.

The cutting blades as above stated, are transversely V-shape, and a further aim of the invention is to so relate the converging sides of said blades, that when the tool is shifted forwardly 65 after nicking grooves in the stock, said blade sides will be free of contact with the sides of said grooves, only the cutting edges of the blades being in contact with the stock, in the bottoms of said grooves. Upon the next operation of the 70 tool therefore, these blades may more easily cut further through the stock.

When cutting relatively small stock, it is desirable that the cutting edges of the blades come into contact with each other, preferably 75 throughout their lengths but at least at their toes, when the hand levers are fully closed. A further object of the invention however, is to provide for quickly and easily moving the cutting levers with respect to the hand levers, to attain 80 this result. In all other similar tools, the cutting edges are adjusted further toward each other, only as said edges are worn and ground away. In the present tool, the toggle is lengthened for cutting small or medium stock where less power is 85 needed, and for maximum size stock which requires more power, the toggle is shortened, providing such power.

With the foregoing and minor objects in view, 90 the invention resides in the novel subject matter hereinafter described and claimed, description being accomplished by reference to the accompanying drawing.

Fig. 1 is a side elevation with the rear ends of 95 the hand levers broken away, and it may here be stated that due to the fact that these levers always cause the toggle connection to exert maximum leverage upon the cutting blades, they may be much shorter than in conventional bolt cutters. 100

Fig. 2 is an edge view.

Fig. 3 is a side elevation partly broken away and in section showing the offset front end of one of the hand levers, the adjustable section of this hand lever for connection with the rear end 105 of one of the cutting levers, and the means for adjusting said adjustable section to vary the spacing of the cutting blades.

Fig. 4 is a transverse sectional view on line 4—4 of Fig. 3. 110

Fig. 5 is an edge view of the adjustable lever section shown in Fig. 3.

Fig. 6 discloses a side elevation and a sectional view of a spring washer which is embodied in the 5 adjusting means for the adjustable lever section.

Fig. 7 is a side elevation of one of the cutting levers.

Fig. 8 is a side elevation of one of the cutting blades and its attaching means.

10 Fig. 9 is an end elevation of the blade and attaching means shown in Fig. 8.

Fig. 10 is a transverse sectional view on line 10—10 of Fig. 1.

15 A preferred construction has been shown and will be specifically described, with the understanding however, that variations may be made within the scope of the invention as claimed.

20 Two cutting levers 12 are shackled together and fulcrumed near their front ends, the front ends of said levers having cutting blades 13 while the rear ends of said levers are connected by a toggle connection 14 with the front ends of the hand levers 15, all of said levers 12 and 15 being suitably ribbed for reinforcing purposes.

25 In the present showing, two shackle links 16 are disposed at opposite sides of the cutting levers 12 and are connected therewith by fulcrum pins 17 in the form of screws, the levers being preferably provided with hardened bushings 18 engaging said fulcrum pins. I have shown a construction for a heavy duty tool using center cut jaws but I do not wish to be confined to that construction. For side, angular or end cutting, I use a removable, adjustable cutting jaw that is secured 30 to jaw levers differently.

35 The front ends of the levers 12 are straddled by channel-shaped attaching members 19 which carry the transversely V-shaped blades 13, said attaching members 19 being detachably secured 40 to the levers by screws 20 so that the blades 13 may readily be removed for grinding, or other blades, even shearing blades (for flat stock, steel cables, etc.) may be applied.

45 The angle between the converging sides 21 of each blade 13, decreases from the front to the rear end of said blade as shown in Fig. 9, and when the tool is set for cutting large stock, the cutting edges 22 of the blades 13 always converge forwardly, even when the hand levers 15 are fully closed, as in Fig. 1. When these levers are opened into substantially 60° relation with each other, the maximum sized stock to be cut by the tool, may be received between the front ends of the blades 13. Closing of the hand levers 15 then causes the toggle connection 14 to exert maximum leverage upon the levers 12, so that the front ends of the blades 13 easily form two grooves or nicks in opposite sides of the stock. The levers 15 are then again opened into substantially 60° relation and the tool is pushed forwardly upon the stock until the cutting edges 22 of the blades again contact with the stock, in the bottoms of the grooves. A second closing of the levers 15 then causes these blades to cut further through the stock, and these operations are repeated as many times as necessary, until the stock is sufficiently severed to cause it to break apart when making the last cut. Due to the gradual rearward reduction in the angle between the blade sides 21, each time these blades are moved forwardly, said sides 21 thereof, will clear the sides of the grooves previously cut into the stock, only the cutting edges 22 of the blades being in contact with said stock. It is thus insured that the blades may more easily 70 cut further through the stock upon the next op-

eration of the tool. Moreover, the successive advances of the tool bring the stock gradually nearer to the fulcrums of the cutting levers, increasing power.

80 The front ends of the hand levers 15 are provided with intermeshing knuckles 23 which are inwardly offset from the body portions of the levers, said knuckles being connected with each other by a suitable fulcrum pin 24. Suitable hardened metal bushings such as 25 of Figure 3, may be used wherever advisable in the pivotal connection between the levers 15. These levers carry adjusting sections in the form of short levers 26. These levers 26 are fulcrumed between their ends to the hand levers 15, as shown at 27 and the front ends of said levers 26 are pivoted at 28 to the rear ends of the cutting levers 12, said levers 12 being preferably bifurcated to receive said front ends of the levers 26. Adjusting eccentrics 29 are carried by the levers 15 and engaged at diametrically opposite points with longitudinally extending portions of the rear ends of the levers 26 for swinging the latter either inwardly or outwardly about their fulcrums 27, to vary the spacing between the cutting edges 22, as may be required, 90 and to hold said levers 26 against movement in either direction with respect to the hand levers 15, after adjustment of said levers 26. These eccentrics, as will hereinafter become more apparent, may be very quickly and easily turned to effect the desired adjustment, either to dispose the cutting edges 22 in diverging relation when the tool is closed, or to insure that said edges shall contact with each other throughout their lengths when the tool is in closed position. When the levers 26 have been adjusted to dispose the cutting edges 22 in diverging relation as in Fig. 1, the eccentrics 29 stand substantially on dead center, and to adjust said levers 26 to dispose said cutting edges 22 in contact, said eccentrics are turned 100 one-half revolution so that they again stand substantially on dead center. No positive locking means is therefore necessary to hold these eccentrics against accidental turning during operation of the tool. A frictional holding means, however, 105 is preferably provided and will be hereinafter described in its preferred form.

110 The pivots 24 and 28 and the associated structure of the tool, form the toggle 14 and the eccentrics 29 constitute means for either shortening or lengthening this toggle, to effect such movement of the cutting levers 12 as to bring about any desired relation of the cutting blades 13. When the hand levers 15 are fully closed, the toggle is absolutely straight, the pivots 24 and 28 being then in alignment, and due to the fact that said hand levers are never opened much if any beyond 60° relation, the toggle is never broken sufficiently to cause it to exert only little force upon the levers 12 upon re-closing of the levers 15.

115 In the construction herein disclosed, each hand lever 15 is provided with a recess 30 which opens forwardly and preferably opens also to the outer longitudinal edge of the lever. This recess 30 of each lever 15 receives the adjusting section or lever 26, and the fulcrum pin 27 of this part 26, extends across the front end of the recess. The front end of the lever or the like 26 projects forwardly from the recess 30 for connection with the cutting lever 12. The rear end of this lever or the like 26 however, is confined within the recess 30 and is formed with an opening 26' which receives the eccentric 29, this eccentric being also confined 120 in the recess 30. Two of the walls of the opening 26' extend longitudinally of the lever 26, and dia-

metrically opposite points on the periphery of the eccentric 29 abut said walls at all times, holding said lever 26 against movement in either direction with respect to the lever 15, after the eccentric has 5 been turned to adjust said lever 26. When the eccentrics are in either of their extreme positions, they lie against the rear ends of the openings 26' and have no tendency to swing from these positions during operation of the tool. A short shaft 10 31 carries the eccentric 29 and is connected with the latter by a key 32, said shaft being preferably in the form of a bolt having a head 33 at one end and a nut 34 at its other end, said head and nut being countersunk in openings 33' and 34', formed 15 in the lever 15. The head 33 is formed with a screw driver kerf 35, and by inserting a screw driver therein, the shaft 31 may be quickly and easily turned, thereby rotating the eccentric 29 and causing the latter to swing the adjusting lever 26 about its fulcrum 27.

20 A spring washer 36, normally of the shape shown in Fig. 6, surrounds and is keyed to the shaft or bolt 31 and serves to hold the eccentric 29 tightly against one side wall of the recess 30, so as to prevent any accidental shifting of said 25 eccentric from the position to which it is adjusted. Friction caused by the washer 36 however, is insufficient of course to prevent proper hand turning of the eccentric whenever the tool 30 is to be adjusted for one size stock or another. In the present showing, the lever or the like 26 is formed with a lateral recess 37 in which the washer 36 is received.

35 It will be seen from the foregoing that a novel and advantageous metal cutting tool has been provided, including unique provision for easily cutting even maximum sized stock, by a series of cutting operations, in all of which the hand levers and the toggle connection exert maximum 40 leverage upon the cutting levers. It will further be observed that a unique and advantageous cutting blade structure has been provided, and that readily accessible and quickly adjustable provision has been made for varying the spacing of 45 the cutting blades as required.

45 While the details disclosed may be considered as preferred, as above stated, attention is again invited to the possibility of making variations.

I claim:—

50 1. A metal cutting tool comprising two cutting levers shackled together and fulcrumed near their front ends, and two hand levers having a toggle connection with the rear ends of said cutting levers, the front ends of said cutting levers 55 being provided with longitudinal transversely V-shaped cutting blades whose cutting edges diverge forwardly to such an extent that the maximum size stock to be cut by the tool may enter between the front ends of said cutting edges when said hand levers are only approximately 60° apart, said cutting edges being also in forwardly diverging relation when said hand levers are fully closed, the angle between the converging sides of said transversely V-shaped cutting 60 blades being gradually decreased from the front to the rear ends of said blades, whereby one operation of the tool with the front ends of said cutting blades engaged with the stock, will cut two V-shaped grooves in the stock, and advancing the cutting blades in said grooves will move said converging sides of said blades from contact with the converging sides of said grooves preparatory to another operation of the tool to further cut through the stock.

65 2. In a metal cutting tool, two transversely

V-shaped cutting blades and means for operating said blades to engage them with opposite sides of the stock to be cut, the angle between the converging sides of said V-shaped blades being gradually decreased from one end of said 80 blades to the other end thereof, whereby one operation of the tool with the stock between the wide-angled ends of the blades will cut V-shaped grooves in the stock, and relative shifting of tool and stock to dispose the latter further toward the narrow-angled ends of the blades will move the converging sides of said blades from contact with the sides of said grooves preparatory to a second operation of the tool to further cut 85 through the stock.

3. A metal cutting tool comprising two cutting levers shackled together and fulcrumed near their front ends, said cutting levers having longitudinal cutting blades so shaped as to be capable of contact with each other at their toes, two hand levers pivoted together at their front ends, means co-operable with the pivot of said hand levers in forming a toggle connection between said hand levers and the rear ends of said cutting levers, and adjustable means for 90 lengthening said toggle connection sufficiently to dispose said toes of said blades in contact with each other when said hand levers stand closed, and for shortening said toggle connection sufficiently to dispose said cutting edges in widely 95 diverging relation when said hand levers stand closed.

4. A metal cutting tool comprising two cutting levers shackled together and fulcrumed near their front ends, said cutting levers having cutting 100 blades, two hand levers pivoted together at their front ends and having pivotally mounted adjusting sections, the front ends of said adjusting sections being pivoted to the rear ends of said cutting levers, and rotatable manually adjustable eccentrics mounted on said hand levers for swinging said adjusting section either inwardly or outwardly to vary the spacing of said cutting blades, said eccentrics being mounted on axes parallel 105 with said pivots, each of said adjusting sections 110 having spaced longitudinally extending portions which always abut its respective eccentric at substantially diametrically opposite points, whereby said adjusting sections are held against movement in either direction with respect to said hand levers 115 after adjustment of said adjusting sections.

5. A metal cutting tool comprising two cutting levers shackled together and fulcrumed near their front ends, two hand levers having their front ends offset toward each other and pivoted together between the rear ends of said cutting levers, said hand levers having recesses behind 120 said cutting levers, two adjusting levers fulcrumed in said recesses respectively, the front ends of said adjusting levers projecting forwardly 125 from said recesses and being pivoted to the rear ends of said cutting levers, the recess-contained portions of said adjusting levers having openings, eccentrics rotatably mounted on said hand levers within said openings for adjusting said adjusting 130 levers either inwardly or outwardly to vary the spacing of said cutting levers, each of said eccentrics abutting longitudinal walls of the adjusting lever opening in which it is received at substantially diametrically opposite points, whereby both 135 adjusting levers are held against movement in either direction with respect to said hand levers after adjustment of the former, and means for mounting and rotating said eccentrics.

6. A metal cutting tool comprising two cutting 140

- levers shackled together and fulcrumed near their front ends, two hand levers having their front ends offset toward each other and pivoted together between the rear ends of said cutting levers, said hand levers having recesses behind said cutting levers, two adjusting levers fulcrumed in said recesses respectively, the front ends of said adjusting levers projecting forwardly from said recesses and being pivoted to the rear ends of said cutting levers, the recess-contained portions of said adjusting levers having openings, eccentrics within said openings for adjusting said adjusting levers either inwardly or outwardly to vary the spacing of said cutting levers, each eccentric contacting at substantially diametrically opposite points with longitudinal walls of the adjusting lever opening in which it is received, each eccentric being adapted to always stand substantially on dead center, short manually rotatable shafts on which said eccentrics are slidably keyed, said hand levers having bearing openings in which said shafts are rotatably mounted, and spring washers on said shafts for holding said eccentrics frictionally against one side of said recesses.
7. In a metal cutting tool, a hand lever having an offset front end formed with pivot means, said lever having a forwardly opening recess near said offset end, a pivot pin extending through said lever and across the front end of said recess, a short manually rotatable shaft extending through said lever and across the rear end of said recess, an eccentric mounted on said shaft and disposed within said recess, and an adjusting lever received in said recess and having its front end projecting therefrom and formed with pivot means, said adjusting lever being fulcrumed on said pivot pin and having an opening receiving said eccentric, said opening having walls extending longitudinally of said adjusting lever and contacting with said eccentric at substantially diametrically opposite points.
8. A structure as specified in claim 7; together with a spring washer around said bolt within said recess for holding said eccentric against one side of said recess.
9. A metal cutting tool comprising two cutting levers shackled together and fulcrumed near their front ends, said cutting levers having cutting blades, two hand levers pivoted together at their front ends and having pivotally mounted adjusting sections, the front ends of said adjusting sections being pivoted to the rear ends of said cutting levers, and two manually rotatable eccentrics mounted on said hand levers respectively, said eccentrics being engaged with said adjusting sections respectively and being operable when turned to one dead center position to so swing said adjusting sections as to dispose the toes of said cutting blades for contact upon closing of said hand levers, said eccentrics being further operable when turned to a second dead center position to so swing said adjusting sections as to dispose said cutting blades for diverging relation upon closing of said hand levers.
10. A structure as specified in claim 9; together with means for frictionally holding said eccentrics in both of said dead center positions.
